ATTORNEYS

UNITED STATES PATENT OFFICE.

GUSTAV L. JAEGER, OF NEW YORK, N. Y.

MATCH-BOX.

SPECIFICATION forming part of Letters Patent No. 281,075, dated July 10, 1883.

Application filed May 17, 1883. (No model.)

To all whom it may concern:

Be it known that I, GUSTAV L. JAEGER, a citizen of the United States, residing at New York, in the county and State of New York, have invented new and useful Improvements 5 in Match-Boxes, of which the following is a specification.

This invention is especially adapted to boxes for holding that class of matches which are 10 composed of strips of pasteboard or other similar material; and it consists in a flat rectangular box having one of its edges provided with an opening to admit the thumb and forefinger, in combination with a spring of novel 15 construction arranged within the box to press in the direction of said edge, so that the matches which may be put in the box are held in contact with said edge for their convenient withdrawal through the opening.

20 It also consists in a flap attached to the box to protect the thumb in igniting the matches, such flap being adapted to be lifted for inserting a match thereunder, and then depressed on the match.

25 This invention is illustrated in the accompanying drawings, in which Figure 1 represents a side view. Fig. 2 is a longitudinal section. Fig. 3 is a cross-section on the line $x-x$ Fig. 1. Fig. 4 is a similar section on the line 30 $y-y$, Fig. 2. Figs. 5, 6, and 7 illustrate a modification of the spring. Fig. 8 shows a modification of the flap.

Similar letters indicate corresponding parts.

The letter A designates the body of the box, 35 which is flat and rectangular in outline. B is the finger-opening in one edge of the box; C, the pressure-spring, and D the thumb-protecting flap.

The opening B is made of sufficient depth to 40 conveniently admit the thumb and the forefinger for withdrawing the matches, which are held in contact with said edge of the box having the opening by the action of the spring C.

In the example shown in Figs. 1 to 4, inclusive, the spring C is composed of a piece 45 of wire, which is attached to one edge of the

box to lie against one side thereof, and is bent at the free end toward the other side of the box, forming a finger, e. This finger is the part of the spring which acts upon the matches, and since the body of the spring clears the matches, said finger is adapted to take the proper position for allowing the box to be filled, as indicated in Fig. 2. Said spring, 50 however, may also be composed of an elastic band, which passes around the matches, and thence through a slot in the edge of the box, having the opening B around the opposite edge of the box, as shown in Figs. 5, 6, and 7, it thus serving the additional purpose of keeping the box closed; and I reserve the right to make this spring the subject of a separate application for Letters Patent.

The flap D is attached to the box on one edge, as at f, by a joint, which permits it to be 65 lifted for inserting a match thereunder, and then depressed on the match and is roughened on its under surface, as shown in Figs. 1 and 3; or, in lieu thereof, the box may be roughened opposite to the flap, as shown in Fig. 8, so 70 that if a match is drawn under the flap in the proper manner it is ignited.

What I claim as new, and desire to secure by Letters Patent, is—

1. The combination, with the box having 75 an opening for withdrawing the matches, of the thumb-protecting flap D, adapted to be lifted for inserting a match thereunder, and then depressed on the match, substantially as and for the purpose described.

2. The combination, with the box having the finger-opening B in one edge, of the wire 80 spring arranged in the box, and provided with the finger e, substantially as and for the purpose described.

In testimony whereof I have hereunto set my hand and seal in the presence of two subscribing witnesses.

GUSTAV L. JAEGER. [L. S.]
